UNITED STATES PATENT OFFICE.

JAMES L. KERSTETTER, OF BRADFORD, PENNSYLVANIA, ASSIGNOR OF ONE-HALF TO F. W. WINGER AND F. W. WAGNER, OF BRADFORD, PENNSYLVANIA.

INKSTAND.

SPECIFICATION forming part of Letters Patent No. 691,721, dated January 21, 1902.

Application filed May 24, 1901. Serial No. 61,753. (No model.)

To all whom it may concern:

Be it known that I, JAMES L. KERSTETTER, a citizen of the United States, residing at Bradford, in the county of McKean and State of 5 Pennsylvania, have invented a new and useful Inkstand, of which the following is a specification.

The present invention relates to inkstands; and one object thereof is to provide an improved closure for the dip-opening of the ink-receptacle, which closure will be automatically operated when the pen is laid upon the rack and at the same time will permit of the ink-receptacle being readily filled or removed 15 for the purpose of cleansing.

A further object is to provide an improved device for regulating the depth to which the pen may be inserted in the ink-receptacle, whereby an abnormal amount of ink upon the 20 pen, with its consequent inconveniences, may be avoided.

In the following specification there is described the preferred embodiment of this invention, and the same is also illustrated in 25 the accompanying drawings; but such slight changes may be made therefrom as are within the scope of the appended claims.

In the drawings, Figure 1 is a perspective view of an inkstand embodying the present 30 invention. Fig. 2 is a longitudinal sectional view through the same. Fig. 3 is a sectional view through the dip-tube, showing a pen inserted therein. Fig. 4 is a view similar to Fig. 3, but illustrating the pen inserted in a 35 different manner. Fig. 5 is a detail vertical sectional view through the dip-tube, taken at substantially right angles to the section shown in Figs. 3 and 4.

Similar numerals of reference designate 40 corresponding parts in all the figures of the drawings.

In carrying out the invention a pen-rack is provided, which consists of a base-ring 10, supported by suitable feet 11 and having upon 45 diametrically opposite portions upright standards 12. These standards each carry at its upper end keeper branches or prongs 13, the rear prong being preferably in the form of a hook. Interposed between these prongs is an 50 intermediate separator-prong 14, which is pro-

vided with a downwardly-extending slot 15, having its upper end open.

An ink-receptacle 16 is seated within the ring 10 and has an annular shoulder 17, which rests thereon. This receptacle may be of any 55 desired construction, but is preferably made of glass, and has a suitable dip-opening 18 contiguous to its front end. Beneath this opening is located a cylindrical depending well 19. For the purpose of closing the dip- 60 opening 18 a cover (designated as a whole by the reference-numeral 20) is pivoted upon the pen-rack. This cover consists of a suitable cap 21, having a neck 22, that is secured to a counter weight or balance 23, which counter- 65 balance is provided at its end edges with trunnions 24, that are detachably seated in the lower ends of the slots 15 of the intermediate separator-prong. When in position, the neck 22 projects across the space between the front 70 and intermediate prongs 13 and 14 of the respective standards, and the counterbalance 23 is sufficient to normally hold the cover in raised position, as indicated in dotted lines in Fig. 2.

Arranged in the dip-opening 18 of the ink-receptacle is the dip-regulating tube 25, preferably provided with external screw-threads at its upper end, said upper end also having an outstanding flange 26. The lower end of 80 the tube is contracted by means of converging stop wings or shoulders 27, the free ends of which are spaced a slight distance apart and leave lateral inlet-openings 28. A supporting-collar 29 is fastened to the walls of 85 the dip-opening 18 and is provided with internal screw-threads. The regulating-tube 25 is threaded into this collar and can be rotated therein to regulate the distance between the stop wings or shoulders 27 and the 90 bottom of the well 19.

The operation of the several elements is as follows: As long as there is no weight upon the cap 21 or the neck 22 the counterbalance 23 will hold said cap in raised position, and 95 the dip-tube is therefore readily accessible to a person using the same. When the person has finished writing, it is only necessary for him to lay his pen between the front and intermediate prongs 13 and 14, whereupon the rec-

said pen will bear upon the neck 22, and because of this additional weight the front portion of the cover will be lowered and the cap will be brought upon the upstanding portion 5 of the regulating-tube 25, thus closing the ink-receptacle. When it becomes necessary to fill the receptacle, the entire cover may be removed by sliding the trunnions from the open ends of the pivot-slots 15, thus giving 10 sufficient room for the necessary movement of the mouth of the supply-bottle. When the cover has thus been removed, the ink-receptacle may also be readily taken from the supporting-ring for the purpose of cleansing. 15 Should the level of the ink within the receptacle be near the top of the same the tube is rotated, so as to raise it to a suitable height, and as the ink lowers by rotating it in the opposite direction the lower end will be correspondingly lowered, so that a sufficient quantity 20 of ink will always be assured. The connection between the supporting-collar 29 and the tube is air-tight, so that the height of the ink within the tube will be regulated by the 25 lateral inlet-openings 28, and in case a small pen is employed the tube is rotated so that the wings will be across the same or in substantially the position shown in Fig. 3. The side shoulders of the pen will thereupon bear 30 against these wings and the point will not project between the same. If, however, a longer pen is used and one that will hold a greater quantity of ink, the tube is rotated until it is substantially at right angles to the 35 position shown in Fig. 3 or in the relation shown in Fig. 4. The point of a pen when inserted while the tube is in this position will pass between the lower ends of the stop wings or shoulders 27 and the movement will be 40 stopped by the inner shoulders of said pen. It thus can be dipped farther than when in the above-described position.

From the foregoing it is thought that the 45 construction, operation, and many advantages of the herein-described invention will be apparent to those skilled in the art without further description, and it will be understood that various changes in the size, shape, proportion, and minor details of construction 50 may be resorted to without departing from the spirit or sacrificing any of the advantages of the invention.

Having thus described my invention, what I claim as new, and desire to secure by Letters Patent, is—

55

1. The combination with a pen-rack comprising a base-ring, standards located at diametrically opposite points of the ring, each of said standards being provided with spaced keeper-prongs and an intermediate separator-prong having a longitudinally-disposed slot which is open at its upper end, an ink-receptacle seated in the base-ring and provided with a dip-opening, a cover for the dip-opening having oppositely-disposed pintles 60 detachably mounted in the slots of the intermediate separator-prongs and counterweighted so as to be normally held away from the dip-opening, said cover projecting across the space between the prongs of the respective 70 standards and arranged to be engaged and moved over the dip-opening by a penholder placed between said prongs.

2. An ink-receptacle having a dip-opening, a dip-regulating device located in said opening, and stop means carried by the regulating device, said stop means being movable to different positions and arranged to be engaged when in such different positions by different portions of a pen inserted in the dip-opening to limit the depth of movement of 80 the same.

3. An ink-receptacle having a dip-opening, a dip-regulating tube rotatably mounted within the dip-opening and carrying oppositely-disposed stop-shoulders which are movable to different positions and are arranged to be engaged when in such different positions by different portions of a pen inserted in the dip-opening to limit the depth of movement of 90 the same.

4. An ink-receptacle having a dip-opening, a dip-regulating tube rotatably mounted in the opening and carrying oppositely-disposed converging stop-wings, the lower ends of 95 which are spaced apart.

In testimony that I claim the foregoing as my own I have hereto affixed my signature in the presence of two witnesses.

JAMES L. KERSTETTER.
